(57) **CLAIM**

We claim the ornamental design for a computer input device, as shown and described.

DESCRIPTION

FIG. 1 is a perspective view of a computer input device. FIG. 2 is a first side view of the computer input device shown in FIG. 1.

FIG. 3 is a second side view of the computer input device shown in FIG. 1.

FIG. 4 is a front view of the computer input device shown in FIG. 1.

FIG. 5 is a rear view of the computer input device shown in FIG. 1.

FIG. 6 is a top view of the computer input device shown in FIG. 1; and,

FIG. 7 is a bottom view of the computer input device shown in FIG. 1.

The broken lines having equal segments represent portions of the article that form no part of the claimed design.

1 Claim, 6 Drawing Sheets
